Primary Examiner — Amber R Stiles*Assistant Examiner* — Kellianne M Shaver(74) *Attorney, Agent, or Firm* — Bochner PLLC; Andrew D. Bochner(57) **CLAIM**

The ornamental design for a cigar glass, as shown and described.

DESCRIPTION

FIG. 1 is a perspective view of a cigar glass;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view, showing the cigar glass in use. In the drawings, the broken lines depict environment and define the bounds of the claim, and form no part of the claimed design.

1 Claim, 7 Drawing Sheets(56)
